(57) **CLAIM**

The ornamental design for a keyboard having touch display with control icons as shown and described.

DESCRIPTION

FIG. 1 is a front perspective view of a keyboard having touch display with control icons comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a detail perspective view of the keyboard having touch display with control icons, taken from detail '8' shown in FIG. 1; and,

FIG. 9 is a detail top view of the keyboard having touch display with control icons, taken from detail '9' shown in FIG. 6.

The even-dash broken lines shown in the drawings represent portions of the article that form no part of the claimed design. The dash-dot broken lines represent boundaries of

(Continued)

the claims design and form not part thereof. The additional set of even-dash broken lines in FIGS. 1, 6 and 8-9, enclosing portions of the article within detail boxes, represent the extents of the enlarged views and form no part of the claimed design.

1 Claim, 7 Drawing Sheets
